The ornamental design for a belt clip for tape ruler, as shown and described.

DESCRIPTION

FIG. 1 is an isometric pictorial view of a belt clip shown from the front, below and to the right; showing the new design.

FIG. 2 is a front elevational view thereof;

FIG. 3 is a rear elevational view thereof;

FIG. 4 is a right side view of the buckle of FIG. 1, for which the left side view is a mirror image thereof; and,

FIG. 5 is a top view of the buckle of FIG. 1, for which the bottom view is a mirror image thereof.
